(57) **CLAIM**

The ornamental design for an analyte test meter, as shown and described.

DESCRIPTION

FIG. 1 is a perspective view of the analyte test meter, as seen from the front;

FIG. 2 is a front elevational view thereof;

FIG. 3 is a first side elevational view thereof;

FIG. 4 is a rear elevational view thereof;

FIG. 5 is a second side elevational view thereof;

FIG. 6 is a top plan view thereof; and,

FIG. 7 is bottom plan view thereof.

The broken line showing of indicia is included for the purpose of illustrating unclaimed subject matter and forms no part of the claimed design.
